(57) **CLAIM**

The ornamental design for a golf bag, as shown and described.

DESCRIPTION

FIG. 1 is an elevated perspective view of a golf bag showing my new design;

FIG. 2 is a front view of the golf bag of FIG. 1;

FIG. 3 is a right side view of the golf bag of FIG. 1, the left side view being a mirror image thereof;

FIG. 4 is a rear view of the golf bag of FIG. 1;

FIG. 5 is a top plan view of the golf bag of FIG. 1;

FIG. 6 is a bottom plan view of the golf bag of FIG. 1; and, FIG. 7 is an elevated perspective view of the golf bag of FIG. 1 showing the bag in the open condition.
